STOCKING

Filed Sept. 13, 1930

INVENTOR
Henry Peters

BY
Joseph Juhass, *Joseph Juhass*,
ATTORNEY

UNITED STATES PATENT OFFICE

HENRY PETERS, OF CLIFTON, NEW JERSEY, ASSIGNOR TO UNIVERSAL PATENTS HOLDING CO., OF WEEHAWKEN, NEW JERSEY, A CORPORATION OF NEW JERSEY

STOCKING

Application filed September 13, 1930. Serial No. 481,674.

The invention relates to stockings and has for its principal object to provide a full fashioned stocking the blank or web of which is so knitted that it may be made in its entirety on a single machine.

5 Ordinarily the webs or blanks for full fashioned hose are formed on two machines, one known as a legger and the other known as a footer.

10 It is necessary to transfer the partially completed blank from the legger to the footer and as the operation is one of great delicacy the utmost precision and skill must be used or the stocking is ruined. In accordance with the present invention a blank or 15 web is so formed that it may be completely knitted on either a legger or a footer with very slight and minor changes in either standard type of machine.

20 In this manner great economies are effected both as to saving in labor and saving in material, thus eliminating a great amount of waste.

25 A further object is to provide a stocking of excellent appearance and having greater wearing abilities. Runs or breakouts frequently occur at the point where the transfer is made from one machine to another. As this transfer operation is eliminated it 30 naturally follows that a stronger stocking is produced.

Another serious defect with the present methods of manufacture is the fact that the 35 leg portion of the stocking is woven from a run of silk from one set of cones and the foot portion woven from a different set of cones of silk. Naturally, the color is the same but the slightest variations often occur in the shades and in the grades of silk and this 40 becomes particularly noticeable in the completed stocking. In accordance with the present invention the complete stocking is made from a run of silk from the same cones.

45 Other objects and advantages will become apparent as this specification proceeds. Referring to the drawings forming a part thereof and in which a preferred embodiment of the invention is illustrated, the figure represents a plan view of the lower portion of the 50 blank or web from which a stocking or sock

made in accordance with the invention is formed.

The reference numeral 5 designates the leg portion of the stocking. This portion of the stocking is formed with the single main thread carrier in any well known approved manner on a flat knitting machine.

55 At or about the points 6 reinforcing thread carriers begin to function and a pointex heel, a French heel or heel of any desired shape is started. The heel portions 7 are knit in the usual manner until the points 8-9 are reached.

60 At the points 8-9, the main thread carrier and the two reinforcing thread carriers are given a one needle outward movement 65 preferably in accordance with the instrumentalities outlined in my copending application of even date with this application. While this one needle outward movement is desirable in order to maintain a proper selvage and nice lines for the hose, the ultimate result could be accomplished, although not in so satisfactory a manner, by a two needle outward movement.

70 During this widening operation from the points 8-8 and 9-9 the main thread carrier is traversing the full width of the web and two reinforcing thread carriers heretofore mentioned are operating between the lines 75 10-10 and 11-11. Prior to the points 12-12 being reached the narrowing fingers function in the usual manner in cooperation with the frame needles and thread carriers 80 to provide the inward narrowing 13-13 desirable for a full fashioned hose.

85 At the points 12-12 the main thread carrier is brought inward to the points 14-14 and the needle bar is manipulated in the usual manner to form lines of loose-coursing 90 15-15. The main thread carrier then continues to traverse the width of the web from points 14-14 and the reinforcing thread carriers heretofore mentioned form the ravel courses 16-16 which are desirable for the 95 looping operation necessary to complete the stocking.

At or about the points 9-9 a second pair of reinforcing carriers begin to function. The last mentioned reinforcing carriers traverse 100

the stocking blank between the lines 17—17 and 18—18. After the ravel courses 16—16 have been knit the first pair of reinforcement thread carriers may cease to function. From the points 14—14 the sole portion of the stocking is formed, the main thread carrier traversing the web from one edge 19 to the other edge 19 and the second mentioned pair of reinforcing thread carriers continuing to function between lines 18—18 and the edges 19—19.

At this point it is desired to call particular attention to the lines 11—11 and 17—17. As heretofore stated the first mentioned pair of reinforcement thread carriers moves between the lines 10—10 and 11—11 and the second mentioned pair of thread carriers move between the lines 17—17 and 18—18. The result of this arrangement is an overlap 20 or what is known as a split between the lines 11 and 17. This overlap or split is marked 21 and is considered an important feature of the invention. The threads are all interwoven at 21 and the construction is therefore 25 very strong, thus eliminating all chances of runners starting at the overlap or split. In known practice where a legger and footer are employed to make the blank this region of the stocking is unduly weak.

32 The customary narrowing by a one or two needle movement, the one needle movement being preferable, is made at 20—20. From here on the web or blank may be knitted in any well known manner.

35 The complete stocking may be knitted on either a legger or a footer. The only changes necessary in either machine or knitting the complete stocking are slight changes in the carrier attachment permitting the carriers 40 to narrow outward in addition to the customary inward narrowing, and adding an additional rocker flange for the loose-course 15—15. If the complete stocking is knitted on the footer, the narrowing in the toe portion 45 will be formed by the double narrowing-fingers and such narrowing is indicated at 22—22.

50 The ordinary legger is provided with single narrowing fingers and in knitting the complete stocking on a legger the narrowing will appear as indicated 23. The usual loose course 24 and ravel courses 25 are provided for the toe looping.

55 If desired the legger may be equipped with wide and narrow narrowing fingers as used on the footer, or only the wide narrowing finger of the footer, and in the manner the usual full fashioned toe portion may be 60 formed on the legger.

65 The shape and designs of the reinforced parts of the web may be widely varied, for instance the portions 7 or the lines 18 may be of any desired conformation always providing the split or overlap 21 is maintained.

In the completed web all the wales and courses are at right angles to each other.

Such changes as might be made by one skilled in the art are to be considered as coming within the spirit of the invention and the 70 scope of the appended claim.

I claim:

A blank or web for a full fashioned hose, 75 said blank being knitted in its entirety on a single flat knitting machine, the main thread of said blank being continuous over substantially the entire area of said blank, the upper heel portions having reinforced areas formed of reinforcing threads looped with the main thread and the adjacent heel and sole portions having reinforced areas formed of other reinforcing threads looped with the main thread and an overlap between said upper heel reinforced areas and said adjacent heel and sole reinforced areas having both reinforcing threads looped with the main thread, said heel portions being formed with an outward carrier movement.

Signed at New York city, in the county of 80 New York and State of New York, this eleventh day of September, 1930 A. D.

HENRY PETERS.
